COMBINED TRAILER AND PONTOON BOAT

Keith Bushfield, San Francisco, Calif.

Application July 18, 1950, Serial No. 174,435

2 Claims. (Cl. 9—1)

1

This invention relates to a combined trailer and pontoon boat.

The principal object of this invention is to produce a readily transportable trailer arrangement which may be quickly hauled over the highways and other suitable terrain and then quickly launched into the water to form a floating structure upon which the towing vehicle, or supplies, may be readily transported over the water.

A further object is to provide a vehicle of this character which will occupy a minimum amount of road space and yet, when in the water, will have a greater width, so as to give the floating structure a great deal of lateral stability.

A further object is to provide means for effectively propelling the pontoon boat, to steer the same, and to maintain it in loading position.

A further object is to provide a means whereby the pontoon boat may be maintained in rolling contact with a larger vessel in such a manner that it will rise and fall with the wave action without injury to the pontoons.

Other objects and advantages will be apparent during the course of the following description.

In the accompanying drawings forming a part of this specification and in which like numerals are employed to designate like parts throughout the same,

Fig. 1 is a side elevation of my pontoon boat, showing the pontoons folded upon the transporting structure;

Fig. 2 is a side elevation similar to Figure 1, showing the pontoons in open position as the same would appear in use in the water;

Fig. 3 is a top plan view of Fig. 2;

Fig. 4 is an end elevation of Fig. 1, looking from the left of the drawings;

Fig. 5 is an end elevation of Fig. 2, looking from the left of the drawing;

Fig. 6 is a cross section taken on the line 6—6 of Fig. 3;

Fig. 7 is a cross sectional view taken on the line 7—7 of Fig. 3;

Fig. 8 is a view similar to Fig. 7, showing the pontoons in folded position;

Fig. 9 is a cross sectional view taken on the line 9—9 of Fig. 3;

Fig. 10 is a similar view, showing the pontoons in closed position;

Fig. 11 is an enlarged fragmentary detail view showing the manner in which the locking eye beams are moved;

Fig. 12 is a cross sectional view taken on the line 12—12 of Fig. 11;

Fig. 13 is a side elevation of the pontoon boat

2

as the same would appear when transporting a vehicle over a body of water;

Fig. 14 is a similar view, showing the vehicle being landed from the pontoon boat;

Fig. 15 is a similar view, showing the manner in which the pontoon boat is beached;

Fig. 16 shows the manner in which the beached pontoon boat may be transported;

Fig. 17 illustrates the manner in which several pontoon boats may be used to form a pontoon bridge; and

Fig. 18 illustrates the manner in which the pontoon boat may be employed as a lighter for transporting supplies to and from a larger vessel.

There are many times when it is advantageous to have a load-supporting trailer which may be transported over the highways and when navigable streams are encountered, to be able to

20 launch the trailer into the water so that it becomes a load-supporting boat capable of transporting heavy loads through the water. Such vehicles are particularly adaptable to military use wherein machines and equipment may be 25 readily transported long distances over highways, rivers and the like, without necessitating the use of bridges in order to accomplish the water crossings. Heretofore, it has been necessary to employ temporary measures, such as flotation tanks, or cable-supported slings, all of which require considerable time, equipment and consequent delay.

Applicant has therefore devised a trailer arrangement which is comparatively light in 30 structure, yet one which may be easily trailed behind a light vehicle, such as a jeep, yet a structure which will support a relatively large load.

In the accompanying drawings wherein for 35 the purpose of illustration is shown a preferred embodiment of my invention, the numeral 5, referring particularly to Fig. 1 and Fig. 4, designates a platform which has attached thereto spaced, foldable wheels 6 which may be folded 40 from the full-line position of Fig. 4 to the dotted-line position of Fig. 1, or the full-line position of Fig. 5.

The forward end of the platform is supported by a pivoted dolly 7, having ground-engaging 45 wheel 8. This dolly is removable when the boat is in the water.

Pivoted to the platform 5 and along each longitudinal margin thereof, are pontoons 9 and 50 11, pivots being shown in 12 and 13 (see Fig. 8).

Each of these pontoons has bunk space as shown

in 14. This space, however, may be used for other purposes if desired.

Pivoted to the forward end of the platform is a ramp 16, the purpose of which will be later seen.

An outboard motor is shown at 17, through the medium of which the boat may be propelled through the water.

In order to lock the pontoons in open position (that is, the position shown in Fig. 5) I provide a series of sliding eye beams 18 and 19 which are enclosed in slide-ways 22 formed in the platform, and are actuated through the medium of racks secured to one side of each of the bottom flanges of the eye beams 18 and 19.

Referring to Fig. 11, it will be noted that the rack is shown at 23 and is engaged by a gear 24, which gear is, in turn, rotated through the medium of a lever 26 and a ratchet 27, actuated by a hand lever 28.

In order to maintain the ramp 16 in either of the positions shown in Fig. 1 or Fig. 3, I employ sliding pins 29 and 31, which have their inner ends mounted within an opening 32 in the ramp, whereby they may be pushed or pulled in one direction or the other through the use of an actuating pin or any other suitable instrument.

The pontoons 9 and 11 each carry an ear as shown at 33 and 34 respectively, which ears form supporting means for the ramp, as will be hereinafter described.

Rotatably mounted at the rear end of each of the pontoons 9 and 11 are tired wheels 36 and 37 respectively, the purposes of which will be later seen.

The result of this construction is that, assuming that the parts are arranged as shown in Fig. 1, and dolly 1 has been placed beneath the forward end of the platform, then it is only necessary to connect a tractor, such as a jeep, to the dolly, after which the pontoon boat may be trailed behind the jeep to any desired place.

Now, assuming that it is desired to cross a body of water, the user retracts the pins 29 and 31 so as to withdraw the ends thereof from ears 33 and 34, which will permit the ramp 16 to drop down against the tongue of the dolly; the pontoons 9 and 11 may now be swung on their pivots 12 and 13 into the position shown in Figs. 2, 3 and 5, after which they are locked in this position; that is, with their tops in parallel alignment with the top of the platform by actuating the levers 26 in such a manner that the gears 24 rack out the eye beams from their position in the platform, into tunnels formed in the tops of the pontoons. These tunnels are shown at 38 (see Fig. 1).

The boat is now moved into the water as shown in Fig. 15, the wheels 6 raised from the position shown in Fig. 4 to that shown in Fig. 5, the motor 17 swung from position shown in Fig. 15 that shown in Fig. 2, and started.

This will hold the front of the boat against the shore or bank, and, after removing the dolly, the ramp 16 will contact the ground so that the jeep or tractor may be driven up the ramp and on to the platform, as shown in Fig. 14.

The ramp is now raised and the pins 29 and 31 are re-engaged with their ears 33 and 34.

The pontoons will now support the jeep and by reversing the motor, the boat may move out from the shore and to any distant point desired.

Assuming that it is desired to move a considerable distance, the bunks 14 may be used by the

crew or occupants of the boat, or if it is desired to use the pontoon boat as a lighter, as, for instance, in loading or unloading a larger ship, then the pontoon boat is backed stern to the side of the ship, as shown in Fig. 18, the motor reversed so as to hold the wheels 36 and 37 against the side of the ship, with the result that where there is wave action, the pontoon boat will roll up and down the side of the ship without danger of damage thereto.

When a plurality of pontoon boats are arranged in side to side relation, they may form a supporting bridge structure whereby large vehicles or heavy traffic may be rapidly transported over a body of water, after which the pontoons may be quickly withdrawn and transported for use at another point.

It is understood that the form of my invention herewith shown and described is to be taken as a preferred example of the same and that various changes relative to the material, size, shape and arrangement of parts may be resorted to without departing from the spirit of the invention or the scope of the enjoined claims.

Having thus described my invention, I claim:

1. A combined trailer and pontoon boat comprising a substantially rectangular platform, supporting wheel means pivoted to said platform for retraction thereagainst, said platform having a generally flat upper surface, a pontoon of greater length than the platform pivotally attached to each of the opposite parallel margins of the platform, each of said pontoons being of generally rectangular shape in cross section and having transversely extending channels therein, the pontoons when in operative positions presenting the upper sides thereof in the plane of the platform and resting on said platform when in stored position, a ramp hingedly connected to the forward end of the platform and extending between the adjacent projecting ends of the pontoons when in operative position, ears carried by the forward ends of the pontoons and cooperating pins slidably mounted in said ramp for locking the pontoons in operative or stored positions, and cooperating rack and gear means carried by the platform adapted upon operation of the gear to project the racks into the channels of said pontoons to support the pontoons in operative positions.

2. A combined trailer and pontoon boat comprising a substantially rectangular platform, supporting wheel means pivoted to said platform for retraction thereagainst, said platform having a generally flat upper surface, a pontoon of greater length than the platform pivotally attached to each of the opposite parallel margins of the platform, each of said pontoons being of generally rectangular shape in cross section and having transversely extending channels therein, the pontoons when in operative positions presenting the upper sides thereof in the plane of the platform and resting on said platform when in stored position, a ramp hingedly connected to the forward end of the platform and extending between the adjacent projecting ends of the pontoons when in operative position, ears carried by the forward ends of the pontoons and cooperating pins slidably mounted in said ramp for locking the pontoons in operative or stored positions, and cooperating rack and gear means carried by the platform adapted upon operation of the gear to project the racks into the channels of said pontoons to support the pontoons in operative positions.

positions, and manually operated means for rotating the gear.

KEITH BUSHFIELD.
